BLAST ACTUATED SAFETY FOR ROCKET LAUNCHERS

Marshall T. Smith, Havre de Grace, Md.

Application April 20, 1951, Serial No. 222,125

4 Claims. (Cl. 89—1.7)

(Granted under Title 35, U. S. Code (1952), sec. 266)

The invention described in the specification and claims may be manufactured and used by or for the Government for governmental purposes without the payment to me of any royalty thereon.

This invention relates to a safety device for rocket launchers of the recoilless type and more particularly to a safety device operated by the blast of a rocket fired from the launcher.

Many of the rockets now in military use are fired electrically by means of squib located in the rocket. The launcher for such a missile contains a firing circuit completed by the squib and adapted to impart electrical impulses to the rocket. If the launcher circuit is closed constantly, a rocket may be inserted, complete the circuit and be fired prematurely, the blast of the projectile offering possibility of serious injury to the operator. Firing circuits in use at present sometimes contain hand operated safety switches. Failure of the operator however to open these switches nullifies their value. It is therefore a primary objective of this invention to provide an automatically operated safety switch for rocket launchers. One factor common to all rockets is the blast of hot gases emitted by each when fired. A second object of the invention is provision of a safety for rocket launchers automatically operated by the blast of hot gases emitted by the rocket when fired. Other objects of the invention will be evident hereinafter.

In broad outline my invention is a switch, mechanically actuated by the rocket blast, which automatically opens the firing circuit of the launcher each time a rocket is fired. A moving part of the switch, actually contacted by the hot gases, is physically of such dimensions that it will prevent loading of the launcher as long as this part is in position to be actuated by the blast. Details of the invention may be seen from the drawings in which:

Figure 1 is a longitudinal section of the breach end of a rocket launcher tube showing our invention and part of a rocket in the firing position;

Figure 2 is an enlarged view of the vane or moving part of my switch;

Figure 3 is an enlarged view of my invention as shown in Figure 1, the dotted lines showing the safety in the loading position;

Figure 4 is a view of the invention seen from above; and

Figure 5 is a diagram of the firing circuit of a conventional launcher showing my invention in the closed or firing position.

Referring in detail to the drawings, a conventional rocket launcher tube 20 is shown with a support 24 mounted on the upper part of its breech portion 22. Extending down over this exit 22 is an actuating arm 28 pivoted on support 24 on an axis transversely of the axis of the tube. A blast vane 30 is integrally connected with one end of arm 28. This vane serves to partially close or obstruct the breech 22 when the launcher is ready to fire. At its end opposite the vane arm 28 carries a pin 32 joining it to connecting rod 34. Rod 34 has a projection 36 integral therewith and a coupling 38. The coupling 38 is fastened directly to a positive positioning push-pull electrical switch 40 of conventional design.

Switch 40 is in series in the firing circuit of rocket launcher 20. Wires 42 and 44 are the firing leads connecting the switch in the circuit. Wire 42 is joined to trigger 26. This trigger is of known design and con-

2

tains a small magneto (not shown) hand operated by means of handle 46. Switch 48 is an operator controlled safety opening or closing the firing circuit. Wire 50 is in series with wire 42 through the magneto and connects the trigger to contact 52 on the rocket launcher. The circuit may be completed through a rocket inserted in the tube, extending now through contacts 56 and 58, wires 60 and 62, and squib 64 in the rocket to contact 54, insulated from the launcher itself. Contact 54 connects through wire 44 to one side of switch 40, from the other side of which extends wire 42.

The operation of my safety is evident from the drawings and the foregoing description. When arm 28 is in the up or loading position, shown in dotted lines in Figure 3, a rocket can be inserted into the launcher. Movement of the arm 28 is transmitted through connecting rod 34 to switch 40, a simple push-pull switch. When arm 28 is up switch 40 is open, breaking the firing circuit of the launcher. Vane 30 is so large that as long as it is in position over the exit of the launcher tube the latter cannot be loaded. Raising the arm of course breaks the firing circuit. Consequently it is impossible to load a rocket in place while the firing circuit is closed. The operator must close the firing circuit after the rocket is in place by pulling back the arm 28 by means of the projecting handle 36. Pulling back on this projection moves the vane into the blast path of a rocket in the launcher. When the arm has been pulled down, and any other safety such as switch 48 closed the rocket launcher is in the firing position. When the trigger is pulled the magneto sends an impulse through the squib and ignites the propellant. The hot gases formed as decomposition products of the propellant create a blast which partially strikes the vane 30. The energy transferred to the flange is sufficient to force the arm up and into the open or dotted line position shown upon Figure 3. Thus the firing circuit is automatically broken each time a rocket is fired. It may be observed that vane 30 serves a dual purpose: (1) to open the safety switch when hit by the rocket blast; and (2) to prevent insertion of a rocket when the safety switch is closed.

In the claims, the term "trigger switch" is to be interpreted as any means by which the firing circuit is energized by and in response to actuation of the trigger, when the safety switch is closed.

My safety is cheap, light, simple and easy to construct. Yet it possesses the ruggedness to withstand severe military usage. That modifications are possible will be apparent to those skilled in the art. I wish therefore to be limited only by the scope of the appended claims.

I claim:

1. In a breech-loading launcher for a rocket wherein the rocket is loaded in an axial direction into the breech end of the launcher tube and has an electrical firing circuit including contacts in its side wall, a launcher tube, a firing circuit carried by said tube including a trigger switch and a safety switch in series, and electrical contacts engaging the contacts of the rocket when the latter is in firing position longitudinally within said tube, a blast vane carried by said tube for movement from a first position within the blast path of a rocket in firing position in said tube, to a second position free and clear of said path, and a connection between said vane and safety switch closing and opening said switch by and in response to movement of said vane to said first and second positions, respectively, said vane when in first position closing said safety switch and obstructing and physically preventing the loading of the rocket into said tube, and when moved from said first position to said second position by the blast of the fired rocket actuating said safety switch to open position through said connection.

2. In a breech loading launcher for a rocket wherein the rocket is loaded in the direction of its longitudinal axis into the breech end of the launcher tube and has an electrical firing circuit including a pair of insulated contacts in its side wall, a launcher tube, circuit means carried by said tube and including a trigger switch, a safety switch and a pair of spring-urged contacts engaging the respective contacts of the rocket when the latter is loaded to predetermined position longitudinally within said tube,

3
a blast vane mounted to said tube for pivotal movement from a first position wherein it is impinged by the blast of a rocket launched from said tube, to a second position free and clear of said blast, and a mechanical connection between said vane and safety switch closing and opening said safety switch by and in response to movement of said vane into first and second positions, respectively, said vane when in said first position positively preventing the loading of a rocket into said tube and when moved from said first position to said second position by the blast of the fired rocket actuating said safety switch to open position through said mechanical connection.

3. In a breech loading launcher for a rocket wherein the rocket is loaded by movement in the direction of its longitudinal axis into the breech end of the launcher tube and has an electrical firing circuit including a pair of insulated contact bands on its side wall, a launcher tube, circuit means carried by said tube and including a trigger switch, a pair of contacts engaging the respective bands of the rocket when the latter is loaded to predetermined firing position longitudinally within said tube, and a safety switch, a blast vane mounted on said tube at the breech end thereof for movement from a first position in and obstructing the path of loading of a rocket into said tube, to a second position free and clear of said path, and a manually operable mechanical connection between said vane and said safety switch to close and open the same by and in response to movement of said vane into first and second positions, respectively, said vane being automatically moved to second position by the blast of a rocket launched from said tube and when moved from said first position to said second position by the blast of the fired rocket actuating said safety switch to open position through said mechanical connection.

4. In a breech loading launcher for a rocket which is loaded by motion in the direction of its longitudinal axis into the breech end of the launcher tube and has an electrical firing circuit including a pair of insulated contact

5
bands on its side wall, a launcher tube, a firing switch, a safety switch carried externally by said tube and including an operating member to open and close said switch, a pair of contacts fixed with said tube and making contact with respective ones of said bands when the rocket is loaded into predetermined position axially in said tube, a blast vane, bracket means fixed on the breech end of said tube and mounting said vane for pivotal movement about an axis external and transverse of said tube, for movement from a first position in the blast path of a rocket loaded into said tube, to a second position free and clear of said path, and a rod pivotally connecting said vane and operating member to close and open said safety switch by and in response to movement of said vane between first and second positions, said vane when in said first position only obstructing said path to positively prevent the loading of the rocket into said tube and being moved to second position by the blast of the rocket when fired from said tube and when moved from said first position to said second position by the blast of the fired rocket actuating said safety switch to open position through said mechanical connection.
